UNITED STATES PATENT OFFICE.

WESLEY WAIT, OF NEWBURGH, NEW YORK.

BRIDGE.

Application filed October 11, 1927. Serial No. 225,546.

This invention relates to improvements in bridges of that type which are used for comparatively short spans and in which columns on opposite shores are connected by floor stringers, the columns extending above the stringers and anchored cables extend over the crowns of the columns and are connected with the stringers on opposite sides of the columns. In bridges of this type, as heretofore constructed, the structural units are joined by bolts and rivets. One of the objects of the instant invention is to provide a structure in which the use of bolts and rivets is obviated to a large extent by the employment of interlocking joints for the connections. The means employed for this purpose are described in detail hereinafter, pointed out in the appended claims and illustrated by the accompanying drawings.

In the accompanying drawings, in which similar reference characters designate corresponding parts,

Figure 1 shows a side elevation, partly in section and partly broken away, of a column and a stringer at an end of a bridge.

Figures 2, 3, 4, 6 and 7 are detail perspective views of several of the structural units.

Figure 5 is a detail perspective view, showing a group of units employed in the formation of an interlock between the column and the stringer.

The drawings illustrate but a single column and stringer construction, which is similar to the other three column and stringer girder structures, so that it is necessary to show and describe but one of them.

Referring to the drawings in detail, a column formed of upper and lower H-sections 10 and 11, respectively, is engaged at its lower end in interlocked relation with the T-shaped foot 12 seated on and secured to the base plate 13 mounted on the pier 14. The flanged sides 15 of the upper column section 10 abut at their lower ends the upper ends of the flanged sides 16 of the lower column section 11. The web 17 of the lower column section is cut away at the upper end between the flanged sides 16 to form the upper transverse seat 18. In the upper part of the web 17 is the vertical slot 19 in a median position and extending through the transverse seat 18. At the inner end of the slot 19 is the lower trans-

verse seat 20. In the upper ends of the flanged sides 16 of the lower column section are the vertical slots 21 in the same plane as the web 17 and with their inner ends coincident with the transverse seat 18. The lower end of the web 22 of the upper column section 10 is cut away between the flanged sides 15 to form the transverse seat 23. The abutting relation of the upper and lower column sections is such that their webs are positioned in the same plane with the transverse seats 18 and 23 spaced apart.

Mounted between the abutting ends of the upper and lower column sections are the ends of the I-shaped girders 24 forming parts of one of the longitudinal stringers of the bridge. The ends of the girders abut and near the end of each are the notches 25 extending transversely through the flanges to the web of the girder. With the girders and column sections in assembled relation, the webs of the girders fit the slots 21 and the flanged sides of the lower column section register with the notches 25 of the girders. The webs of the girders are in the same plane with the webs of the column sections and the lower edges of the webs of the girders are seated on the transverse seats 18 of the lower column sections. Seated in the slot 19 in the web of the lower column section is an end of the transverse girder 26, having its engaged end notched similar to the engaged ends of the longitudinal girders 24. By the mutual engagement of the lower column section and the girders, an interlock of these parts is provided that securely holds them against the stress and strain incident to such structure.

Means are provided for holding the upper column section 10 in upright alinement with the lower column section 11. Placed between the abutting ends of the two sections is positioned the saddle 27. It is provided in its upper part with a vertical slot 28 in which is seated the lower end of the web 22 of the upper column section and in its lower part there is a vertical slot 29 engaging the webs of the girders 24. At its intermediate part the saddle has a transverse opening 30 merging with the slot 29, the transverse opening fitting the upper flanged sides of the abutting ends of the girders. The saddle fits between the flanges of the abutting sides of the upper and lower column sections and serves to hold them

against relative sidewise movement and also against relative movement transversely of the girders.

From the column 10—11 a series of abutting girders 24 extends to an opposite and similar column (not shown) to form one of the longitudinal stringers of the bridge. Beyond the column the abutting ends of the girders are engaged by shoes 31 fitting over the ends. Each shoe has extending through its intermediate part a vertical slot 32 to receive the webs of the girders and in its upper and lower parts it has horizontal slots 33 merging with the vertical slot to receive the flanged sides of the girders. These shoes maintain the engaged girders in alignment and to prevent displacement from their holding positions, they may be bolted to the girders as indicated at 34, Fig. 1. On the shore side of the column 10—11 the girder 24 rests on and is bolted to the bed-plate 35 suitably incorporated in the material of the abutment 36. The column and the girders extending directly therefrom are relatively braced by the oppositely disposed I-shaped braces 37, seated at their lower ends on the girders and engaging at their upper ends the opposite sides of the column section 10. At each end of each brace the web 38 (Fig. 4) is cut away between the flanged sides 39 to form the diagonal seat 40. In the ends of the flanged sides 39 are the slots 41 extending outwardly from the seat 40 in the same plane as the web 38. With a brace in position, the diagonal seats 40 at its ends respectively abut the flanged sides of the column and the girder, the flanges being notched, as at 42, to admit the flanged sides. In position, the webs of the braces and of the column and girders are in the same plane so that the thrust imparted from one member to the other travels in lines directly within such plane.

There is combined with the column and girder structure a suspension means for carrying part of the load. A cable 43, with one end attached to the beam section 44 embedded in the material of the abutment 36 and thereby anchored, extends over the upper end of the column 10—11 to the stringer formed by the girders 24, to which it is yieldingly connected by the means hereinafter described. Mounted on the upper end of the column is the bearing block 45 having a groove 46 across its top to engage the cable. The lower part of the block is shaped to fit between the flanges of the sides 15 of the upper column section 10 and through the lower part of the block extends the slot 47 to fit the upper end of the web 22 of the column section. At the opposite sides of the block are the shoulders 48 to seat on the upper ends of the flanged sides 15 of the column section. The cable in passing over the bearing block can have play either way with but a slight tendency to displace the upper

end of the column and this tendency is opposed by the opposite braces 37. The bearing block is also seated on the upper face of the transverse girder 49 mounted in the upper end of the web 22 of the column section 10. The end of the girder 49 is notched similar to the ends of the girders 24, as shown in Fig. 5, and it is positioned in the slot 50, indicated by dotted lines in Fig. 1, before the bearing block 45 is mounted in place. 75

The connection between the cable and the stringer is provided by the shoes 31 joining the girders 24 of the stringer and also by the saddle 51 (similar to the saddle 27) on the girder 24 on the shore side of the column. In the upper part of each shoe 31 is a slot 52 extending in the direction of the stringer. Bolts 53, extending transversely through the shoes 31 and the saddle 51, form bearings for the sleeves 54 journaled thereon within the upper slots of said members. The cable 43 leads from its anchor 44, over and between the bearing sleeves 53 of the saddle 51, over the bearing block 45, thence successively through the shoes 31 and around the bearing sleeves therein, to the opposite column (not shown). The devious course of the cable around the bearing sleeves effects a braking action on the movement of the cable relative to the stringer so that the strain of a shifting load on the span will be gradually transmitted from one to the other of the cable and stringer. 95

At intervals the cable and stringer are connected by the hangers 55, suitably attached at their upper ends to the cable and at their lower ends to the clips 56 engaging and slidably on the stringer. Each clip (Fig. 6) 56 is provided with a transverse recess 58 to fit the upper flanged side of the engaged girder 24 and a vertical slot 59 merging with the transverse slot to fit the web of the girder. Extending across the vertical slot 60 in the upper part of the clip is the pin 61 around which is secured the lower end of the hanger. The clips are slid onto the girder before the latter is secured in place. The clips adjustable on the girder can be readily positioned to accommodate a perpendicular alignment of the hangers suspended from the cable. At intervals, transverse floor beams 62 are mounted at their ends at intervals along the girder between the clips. 115

By means of the foregoing construction an interlocking joint is provided between the column sections and the girders of the stringer so that the use of bolts and rivets is eliminated to a great extent; also, interlocking joints are provided for the brace members with the column and stringer for a like purpose. Also, simple connections between the cable and stringer are provided for a ready assembly of the parts without the use of bolts or bolts concealed from inspection. 125

What I claim is:

1. In bridge construction, the combination of a stringer and a column in interlocking relation with the column extending above the stringer, with an anchored cable extending from the stringer over the crown of the column, and a shoe mounted on the stringer and having frictional engagement with the cable to permit restricted relative movement between the stringer and the cable.
2. In bridge construction, the combination of a stringer and a column in interlocking relation with the column extending above the stringer, with an anchored cable extending from the stringer over the crown of the column, said stringer comprising a series of abutting girders, and shoes respectively overlapping the abutting ends of the adjacent girders to maintain the girders in alinement, each of said shoes having frictional engagement with the cable to permit restricted relative movement between the stringer and the cable.
3. In bridge construction, the combination of a stringer comprising girders abutting at their ends with shoes overlapping the abutting ends of the girders to maintain the girders in alinement, each of said shoes having a slot parallel to the longitudinal axis of the stringer, an anchored cable extending through the slots of the shoes, and means providing a frictional engagement between the shoes and the cable to permit restricted relative movement between the stringer and the cable.
4. In bridge construction, the combination of a stringer comprising girders abutting at their ends, with shoes overlapping the abutting ends of the girders to maintain the girders in alinement, each of said shoes having a slot parallel to the longitudinal axis of the stringer, an anchored cable extending through the slots of the shoes, and pins mounted in each shoe to extend transversely across the slot therein with the cable extending between the pins to be frictionally engaged thereby.
5. In bridge construction, the combination of supporting and brace members formed of I-sections in inclined relation and with an end of the brace member interlocking with an intermediate part of the supporting member, the interlocking end of the brace member having its web cut away to form a diagonal seat and having its flanged sides provided with median longitudinal slots coincident with the cut away part of the web, the diagonal seat of the brace abutting a flanged side of the supporting member and said flanged side having notches in its flanges to admit the flanged sides of the brace.
6. In bridge construction, the combination of a column and a stringer in mutual interlocking relation at their intermediate parts, means for supporting the outer ends of the stringer on opposite sides of the column, braces extending diagonally between opposite sides of the upper part of the column and the stringer, said braces being interlocked at their opposite ends with the column and stringer respectively, and an anchored cable extending over the crown of the column and connected with the stringer beyond the braces.
7. In bridge construction, the combination of a column and a stringer in mutual interlocking relation at their intermediate parts, the upper part of said column being of I-section, a crown block mounted on the upper end of the column fitting between the flanges of the I-section and having shoulders extending over the ends of the flanged sides and also having a vertical recess engaging the end of the web of the I-section, said block also having a groove in its top extending in the same direction as the stringer, and an anchored cable extending over the crown block in the groove thereof and yieldingly connected with the stringer on opposite sides of the column.

In testimony whereof I affix my signature.

WESLEY WAIT.
